(57) **CLAIM**

The ornamental design for a skin plaster, as shown and described.

DESCRIPTION

FIG. 1 is a front view of the skin plaster;

FIG. 2 is a rear view thereof;

FIG. 3 is a left side elevation view thereof;

FIG. 4 is a right side elevation view thereof;

FIG. 5 is a bottom plan view of the skin plaster, and the top plan view is a mirror image thereof; and,

FIG. 6 is a perspective view thereof.

The broken line showing of parts of the drawings is included for the purpose of illustrating use and environment and forms no part of the claimed design.
